[57] CLAIM

We claim the ornamental design for a massager, as shown and described.

DESCRIPTION

FIG. 1 is a perspective view of a first embodiment of a massager, showing our new design;

FIG. 2 is a side elevational view thereof, with all other sides being identical thereto;

FIG. 3 is a top plan view thereof;

FIG. 4 is a bottom plan view thereof;

FIG. 5 is a side elevational view of a second embodiment of our new design, with all other sides being identical thereto;

FIG. 6 is a top plan view thereof;

FIG. 7 is a bottom plan view thereof;

FIG. 8 is a side elevational view of a third embodiment of our new design, with all other sides being identical thereto;

FIG. 9 is a top plan view thereof; and,

FIG. 10 is a bottom plan view thereof.
